ABSTRACT OF THE DISCLOSURE

A hood comprising two elongated pieces of material secured together along one edge and end to end to form an annular band having a 180° twist therein.

This invention relates to articles of apparel and to related methods for making the same.

The invention is primarily concerned with the provision of an improved hood-scarf, whose principal unique feature is the manner in which it turns or twists below the face to form a drape and which need not be secured or pinned to maintain the shape of the drape. However, as will be seen, the techniques of the invention are readily applicable to additional and different types of apparel, as will become apparent hereinafter.

Accordingly, it is an object of the invention to provide improved articles of apparel and improved techniques for manufacturing the same.

More particularly, it is an object of the invention to derive from a classical geometrical shape a new form of article of apparel having an unusually graceful appearance.

A hood or scarf provided in accordance with the invention will preferably be in the form of a cowl which touches the top of the shoulder of the user, providing protection for the back of the neck and at the same time allowing for an unusually graceful drape of the cloth. This hood-scarf can be adapted to many uses, primarily determined by the fabric employed when the pattern is applied.

By way of example, the hood-scarf of the invention can be used as a rainhood when made of a fabric which is waterproofed and such a hood-scarf can also be made of cotton or silk or the like. Moreover, the hood-scarf can be used as protection against the cold if made of a fabric such as wool, gabardine, jersey or the like. It can, furthermore, be used as protection from the sun if made of a fabric such as terrycloth and so forth.

The article of apparel of the invention can, moreover, be used as a decorative item for formal wear or for wearing to religious services and for this purpose can be made of lace, starched chiffon, embroidered net, or any other light and airy fabric which is of light weight and which is semi-transparent so that the coiffure is protected against ambient atmospheric conditions.

In addition to the provision of a hood-scarf, it is a further object of the invention to provide techniques which are applicable as well to the provision of turbans, bikinis, sun bathing tops and so forth.

Briefly, in accordance with the invention there is provided an article of apparel comprising a Moebius strip of apparel material such as those mentioned above, said strip being in the form of an endless ring having a single 180° twist therein.

The invention will be more clearly understood from the following detailed description of some preferred embodiments thereof, as illustrated in the accompanying drawing in which:

FIGURE 1 diagrammatically illustrates a step in the procedure of forming an article of apparel in accordance with the invention;

2

FIGURE 2 illustrates a pattern before it is assembled to constitute a hood-scarf in accordance with the invention;

FIGURE 3 is a front view of a hood-scarf provided in accordance with the invention;

FIGURE 4 is a side view of the hood-scarf of FIG. 3;

FIGURE 5 is a rear view of the hood-scarf illustrated in FIG. 3; and

FIGURE 6 is an illustration of how the technique of the invention can be applied to another article of apparel such as a sun bathing top.

In FIG. 1 is illustrated a strip of apparel material 10, such as silk, cotton, wool, plastic material and the like.

The strip 10 includes two ends 12 and 14, as well as two faces 16 and 18 which are on opposite sides of the strip and which are both exposed in the view of FIG. 1, due to the fact that a twist 20 is provided in said strip.

The twist 20 is a single twist of 180° and constitutes 20 the instrument by which opposite faces of the strip are concomitantly exposed to the same viewer. A Moebius strip is provided by joining the ends 12 and 14 to one another in a manner which is described more fully hereinafter.

FIG. 2 illustrates a blank pattern 22 for forming a hood-scarf in accordance with the invention, said pattern including an elongated element 24 and a second elongated element 26, these elements or members being connected as shown in FIG. 3 along edges 28 and 28' to form a seam 29 in what will be described as parallel relationship. Each element 24 or 26 may have a corresponding element aligned therewith in face-to-face relationship in the form of a lining 27. These elements may be provided with hems or decorative borders, as desired, in any conventional fashion.

Considered as a whole, the blank pattern 22 has narrow portions 30a and b and 32a and b and a wider portion 34, considered relative to a longitudinal axis of the pattern, which axis may be regarded for purposes of illustration as being represented by the seam 29. The wider portion 34 of the pattern will be employed to form the cowl portion of the hood-scarf of the invention, as will be seen hereinbelow, and to facilitate the shaping of this cowl portion, there is provided in the pattern a V-shaped cut-out having edges 36 extending perpendicularly of the seam 29, said tuck being made permanent by sewing with thread in conventional manner.

It will be noted that element 24 is an elongated element having two ends constituted by narrow portions 32a and 32b and that element 24 moreover has two elongated sides one of which is indicated at 24a and the other of which is constituted by edge 28. It will also be seen that ends 32a and b are oblique relative to edge 24a. Edge 28 is slightly convex.

Similarly, it will be noted that narrow portions 30a and b constitute the ends of element 26 which is elongated and has a side constituted by edge 28' and a second edge 34. Element 26 is shorter than element 24. Ends 30a and b are oblique relative to edge 34. Side or edge 28' is of sinuous shape and is also generally convex. It is, in fact, more convex than is edge 28 and it is centrally provided with the aforesaid cut-out 36.

For assembly, edges 36 are sewed together to form a tuck. Then sides 28 and 28' are connected together thereby forming a hood-like structure as will appear in FIGS. 3-5. One of the thusly connected ends 30a-32a and 30b-32b is then given a one-hundred and eighty degree twist and end 30a-32a is next sewed to end 30b-32b.

In FIGS. 3-5 it is seen that the resulting hood-scarf comprises a top portion 37, a cowl portion 38 and a skirt portion 40, there being an opening 42 for the face, said opening being gracefully attended by the seam 28

and the rear or cowl 38 being appropriately shaped by inclusion of the tuck 36. The twist is indicated at 44, whereat it will gracefully underlie the chin of the wearer, the ends being connected along a seam indicated at 46 provided with the use of thread in any conventional manner.

The hood-scarf thusly fashioned will fall or be draped in graceful folds, as indicated by way of example at 48 and 50, and if desired, a hem 52 may be employed to give the desired finished effect at the lower extremities of the subject article of apparel.

As seen in FIG. 6, the techniques of the invention can be further employed with other articles of apparel, such as for sun bathing tops, the strip 54 being sewed together at seam 56 and a twist 58 being provided to form a Moebius strip and being located in the wider portion of the strip in order to form two cups 60 and 62, between which will be located extremely graceful pleats or folds connecting the cups 60 and 62 together.

It is thus seen that the invention contemplates the provision of an improved article of apparel comprising a Moebius strip of apparel material in the form of an endless ring having a single 180° twist therein. It is to be appreciated that within the strip of apparel material, different materials may be employed, such as, for example, a combination of cloth and suede or cloth and plastic material. There will further be appreciated that the strip may be provided with opposite sides which are differently decorated, or that the strip may be constituted by pieces of material arranged in face-to-face relationship.

It will also be understood that the strip may include relatively wide and narrow portions, the strip being selectively located in the narrow or wider portions, as required in accordance with the article of apparel to be formed.

The method of the invention will involve making an article of apparel by forming a twist of 180° in a strip of apparel material having two ends and connecting these ends together to form an endless ring. Tucks and seams may be provided in the pattern as required in accordance with the article of apparel to be formed.

What is claimed is:

1. An article of apparel for covering the head and neck of a wearer, said article comprising first and second elongated elements, said first element having two ends and two elongated sides one of which is convex, said second element having two ends and two elongated sides one of which is sinuous and generally convex to an extent greater than that of the convex side of said first element, said second element having a tuck cutout formed centrally in the sinuous side thereof with the edges of said tuck cutout being connected together, said convex sides being connected together to form an elongated head and neck-conforming unit having two ends one of which is twisted through a one-hundred and eighty degree turn and connected to the other to form a hood-like section to cover the head of the wearer with a twisted section to cover the throat of the wearer.
2. An article as claimed in claim 1 wherein the ends of the first and second elements are obliquely disposed relative to the respective other elongated sides thereof.
3. An article as claimed in claim 1 wherein said first element is longer than said second element.
4. An article as claimed in claim 1 wherein said first and second elements are of cloth or plastic.
